UNITED STATES PATENT OFFICE.

GUY M. SHERRILL, OF EASTLAND, TEXAS.

SPARK-PLUG ATTACHMENT.

1,296,126.

Specification of Letters Patent.

Patented Mar. 4, 1919.

Application filed June 15, 1918. Serial No. 240,269.

To all whom it may concern:

Be it known that I, GUY M. SHERRILL, a citizen of the United States, residing at Eastland, in the county of Eastland and State of 5 Texas, have invented a new and useful Spark-Plug Attachment, of which the following is a specification.

The subject of this invention is a spark plug attachment and the objects of this invention are, first to produce an attachment which will render the plug useful even after the porcelain is badly cracked or broken, second, to provide an attachment which will prevent short circuiting when the insulating 15 jacket of the spark plug is broken, third, to provide a simple, durable and efficient spark plug.

With the foregoing and other objects in view which will appear as the description 20 proceeds, the invention resides in the combination and arrangement of parts and in the details of construction hereinafter described and claimed, it being understood that changes in the precise embodiment of the invention 25 herein disclosed, can be made within the scope of what is claimed, without departing from the spirit of the invention.

A practical embodiment of the invention is shown in the accompanying drawing, 30 wherein:—

Figure 1 is a view in elevation of the device shown attached to a plug;

Fig. 2 is a section on the line 2—2 of Fig. 1.

Referring to the drawings by numerals of 35 reference:—

In carrying out the invention there is provided a bracket arm formed, preferably, of two strips 1 of sheet metal which are clamped together by rivets 2 or otherwise.

40 One of the ends 3 of these strips is angled and provided with opposed transverse grooves 4. The extreme ends of these upturned portions are clamped together by the screw bolt 5 or otherwise. The grooves 4 as 45 will be seen, lie between the outer or end rivet 2 and the screw bolt 5.

Adjacent the other end of the strips 1 opposed transverse grooves 6 are formed. These grooves are slightly tapering, as shown to

conform to the porcelain casing 7 of the 50 spark plug which they embrace. A screw bolt 8 or the like clamps these ends of the strips together to bind the device firmly in place.

An insulated wire 9 leads from a suitable 55 source of electrical supply, not shown, and is clamped within the grooves 4, and the end of this wire is bared of insulation and held suitably spaced from the binding post or terminal 10 of the spark plug. 60

While a specific form of bracket arm has been shown and described, it is to be understood that any form of clamp or arm capable of holding the wire in proper spaced relation to the terminal may be used. 65

When the spark plug is provided with this attachment a disruptive discharge under high tension is the only discharge possible. This will cause a sparking at the regular spark gap which will ignite the charge in 70 the engine cylinder even though the porcelain casing of the plug be cracked and broken.

If, under such circumstances, the wire 9 and terminal 10 were connected in the usual 75 way, the current would be short circuited between the binding post 10 and the metal casing 11 without the production of the desired spark.

Having thus described the invention, what 80 is claimed as new and sought by Letters Patent, is:—

The combination with a spark plug including an insulating casing, and a terminal, of a bracket adapted to encircle the casing 85 and having an upturned extending end, a line wire clamped in the upturned end and held in spaced relation to the terminal, and means for clamping the upturned end about the wire. 90

In testimony that I claim the foregoing as my own, I have hereto affixed my signature in the presence of two witnesses.

GUY M. SHERRILL.
